(57) **CLAIM**

The ornamental design for a brachytherapy template, as shown and described.

DESCRIPTION

FIG. 1 is a first front perspective view of a brachytherapy template, showing our new design;

FIG. 2 is second front perspective view thereof;

FIG. 3 is a front elevational view thereof;

FIG. 4 is a back elevational view thereof;

FIG. 5 is a fist side elevational view thereof;

FIG. 6 is a second side elevational view thereof;

FIG. 7 is a top view thereof; and,

FIG. 8 is a bottom view thereof.

Portions in broken lines for the purpose of illustrating environmental structure and form no part of the claimed design. The dot-dash broken lines define, but are not included in, the boundaries of the claim design.
